UNITED STATES PATENT OFFICE.

CLARENCE A. LINDSAY, OF NEW YORK, N. Y.

STRIKING-BAG OR OTHER FLUID-RECEPACLE.

No. 821,722.

Specification of Letters Patent.

Patented May 29, 1906.

Application filed June 24, 1905. Serial No. 266,834.

To all whom it may concern:

Be it known that I, CLARENCE A. LINDSAY, a citizen of the United States, residing at New York, in the county of New York and 5 State of New York, have invented certain new and useful Improvements in Striking-Bags or other Fluid-Receptacles; and I do hereby declare the following to be a full, clear, and exact description of the invention, such 10 as will enable others skilled in the art to which it appertains to make and use the same.

My invention relates to elastic and inflatable bags or other receptacles for containing 15 air or gas under pressure, and has for its object an effective closure for the bag or receptacle; and the invention consists in a flexible tube inserted in a neck on the bag or receptacle and through which tube the bag is inflated and the fluid discharged when desired, and other features of construction 20 which will be fully disclosed in the following specification and claims.

In the accompanying drawings, which form 25 part of this specification, Figure 1 represents a vertical section of a striking-bag provided with my invention, and Fig. 2 a like view of the upper part of the same on an enlarged scale.

Reference being had to the drawings and the designating characters thereon, the numeral 1 indicates an elastic inflatable bag or receptacle for a fluid, such as air or gas under pressure, and may be in the form of a striking-bag, as shown, a football, a cushion, or any 35 other preferred receptacle, and the bag or receptacle is provided with a hollow or tubular neck or extension 2.

3 indicates a flexible tube, preferably of 40 rubber, the outer end of which is preferably provided with an annular bead 4 and is stretched over an annulus 5, preferably of wood, in the periphery of which is a groove 6, and the bead 4 extends below the lower end 45 of the annulus 5, as shown in Fig. 2, and forms a shoulder to resist displacement of the annulus and the tube. The tube extends horizontally inward from the annulus 5, then downward in the form of a bulbous 50 member 7, leaving an opening 8 surrounded by a resilient or flexible wall 9, is then contracted at 10 to prevent doubling of the tube, and is provided with a secondary bulb 11, in which is a valve formed by the incision 12 55 and the two opposite concavo-convex walls 13 13.

14 indicates a secondary closure inserted in the opening 8 as an additional element of safety to prevent the escape of fluid from the bag.

60 The annulus 5 is inserted in the neck 2 and a strand of wire 15 applied outside the neck to secure the tube 3 and the neck to the annulus 5. Surrounding the annulus 5 is a band 16 of fabric, coated on both sides with adhesive material, and resembles "tire-tape," which is covered or surrounded by an outer thickness of the neck 17, turned down over the band 16 and securely held thereon by the adhesive properties of the band. The tube 3 70 is thus securely held in the neck 2 of the bag 1 and resists any internal pressure brought to bear upon the bag, which tends to displace the tube, and the pressure of the fluid in the bag surrounding the inner end of the tube 75 holds the walls 13 13 together and prevents ready escape of the fluid through the tube.

75 For the purpose of illustration I have selected a striking or punching bag or cover 18, provided with an opening 19 at one end 80 through which the bag is inserted in its collapsed condition and afterward inflated within the cover 18. The cover 18 is provided with flexible straps 20 20 and securing-cords 21 21. By thus inserting the bag 1 in the 85 cover 18 and inflating the bag 1 after it has been inserted all lacing of the cover 18, whether for use as a striking-bag or a football, is avoided, and the cover made more durable than when laced, besides saving time 90 and the annoyance incident to lacing the cover.

To discharge the fluid contents of the bag 1, the closure 14 is removed, when a suitable 95 implement may be inserted in the tube 3 and the valve at its inner end opened, when the fluid will escape freely.

Having thus fully described my invention, what I claim is—

1. An elastic fluid-receptacle provided with 100 a tubular neck, an annulus within the neck, a flexible tube through which the receptacle is inflated, secured to said annulus and having a bulbous inner end constructed to form a valve exposed to the pressure of the fluid 105 within the receptacle, and a detachable closure in the outer end of said tube.

2. An elastic fluid-receptacle provided with 110 a tubular neck, an annulus within the neck, a flexible tube through which the receptacle is inflated, secured to said annulus, having a bulbous inner end constructed to form a

valve, and a contraction adjacent to said inner end, and a detachable closure in the outer end of the tube.

3. An elastic fluid-receptacle provided with a tubular neck, an annulus within the neck, a flexible tube through which the receptacle is inflated, secured to said annulus and having a valve within the receptacle, an opening sur-

rounded by a resilient or flexible wall, and a detachable closure in said opening. 10

In testimony whereof I affix my signature in presence of two witnesses.

CLARENCE A. LINDSAY.
